UNITED STATES PATENT OFFICE.

FRANK REDICK, OF PARKERTON, WYOMING.

DEVICE FOR SUSPENDING STRINGS OF PIPE AND PREVENTING ALL BLOW-OUTS.

Application filed June 20, 1924. Serial No. 721,293.

To all whom it may concern:

- Be it known that I, FRANK REDICK, a citizen of the United States, residing at Parkerton, in the county of Converse and State of Wyoming, have invented new and useful Improvements in Devices for Suspending Strings of Pipe and Preventing All Blow-Outs, of which the following is a specification.
- 10 The object of my present invention is the provision of a new and novel means for hanging or suspending long strings of pipes in oil wells, as well as controlling the outflow of gas or water which might flow between any two strings of pipes, and consists in the construction, combination and operative association of parts set forth in the following description and specifically pointed out in the appended claims.
- 15 In the drawings:—
- Figure 1 is an approximately central transverse sectional view through pipes suspended and supported in accordance with this invention.
- 20 Figure 2 is a top plan view.
- Figure 3 is a top plan view of one of the bushings.
- 25 Figure 4 is a side elevation thereof.
- Figures 5 and 6 are respectively a top plan and side elevation of another form of bushing.
- 30 Figures 7 and 8 are respectively a top plan and a side elevation of still another form of bushing.
- 35 Figures 9 and 10 are respectively a top plan and a side elevation of a still further form of bushing.
- In stringing and suspending the pipes, in a manner as will hereinafter be set forth, 40 I make use of a crane or derrick having hooks to engage the ears on the bushing. For the purpose of this description it has not been deemed necessary to illustrate the crane or derrick.
- 45 In carrying out my invention the first or service string of pipe is let in the well, the outer pipe, indicated by the numeral 1, is surrounded by a suitable cement foundation, indicated by the numeral 2, the coupling
- 50 3 which is screwed on the outer end of the pipe 1 providing a shoulder that effectively locks the pipe in its foundation. On the foundation 2 there rests the metallic base member 4 of the improvement. The member is in the nature of a rectangular metal casting provided with an outer flange and
- an inner opening surrounded by an annular flange 5. Between the annular flange 5 and the outer flange 6 there are radially disposed ribs 7 provided each with a series 60 of spaced apertures 8 engageable with the hooks of the derrick for properly arranging the base on the foundation. The opening surrounded by the flange 4 is of a size equalling that of the hole in which the pipe 65 1, or rather the coupling 3 on the outer end of the said pipe 1, is received.
- The annular flange 5 is of a greater height than the outer flange 6 and has its inner end provided with a continuous depression 9 providing a pocket for a hydraulic packing to establish a gas and watertight joint between the base and the coupling that rests on the base.
- 70 Drilling is continued until the proper depth is reached. A second pipe 10 made up of suitably connected sections is inserted into the pipe or casing 1, and the coupling on the outer pipe section 10 is removed, and there is screwed upon the said section a 75 bushing 11. The bushing includes a stem portion 12 having its outer end portions enlarged and provided with interior threads 13 to be screwed upon the pipe 10. The bushing is also provided with a head 14. The head, like the hollow stem is rounded in plan and has its bore coincident with the bore of the stem. The head 14 has its inner edge formed with an annular depression 80 providing a pocket 15 for a hydraulic packing. The bore in the head is surrounded by an annular depression 16, and there are threaded ports 17 communicating with the said depression. The remaining pipe sections vary in diameter and are received 85 one within the other, each being provided with a bushing substantially similar to the bushing above described. The head portion of all of the bushings is provided with outstanding downwardly rounded ears 18 for 90 engagement with the hooks of the derrick. A hydraulic packing 19 is forced in annular pockets in the heads of the bushings to establish a gas and watertight joint therebetween. In this manner it will be noted 95 that a tight joint is maintained between the respective strings of pipes in the hole. The stems of the respective bushings extend downwardly and inside of the stems of the next lower bushing and are placed free of 100 said lower bushing, thereby permitting a 105 free but controlled outlet for gas or water 110

that may be coming from between any two strings of casing or pipes.

The stem of each of the bushings, except the stem 12 of the bushing 11, is provided with longitudinal grooves or channels 22 that communicate with annular depressions 20, the groove 22 of the bushing that rests on the bushing 11 communicates with the depression 16. The bushings are provided with threaded ports 21 that communicate with the depressions 20. The ports 17 and 21 are designed to have screwed therein either a valve or a pipe whose passage is controlled by a valve, and in this manner it will be seen that the gas and water between any two of the strings of pipe may be controlled. This is a very important feature of the invention. The ports 17 and 21 may be also used as inlets in case it is desired to pump mud or cement between two strings of pipes. Both the pipe and the base of the bushings are formed from a good grade of steel casting to render the construction strong and durable. The pipe sections may be readily removed when the well is dry or when the drillers fail to locate oil. The improvement enables the driller to absolutely and immediately control the outlet or exhaust of water and gas coming from the hole without interfering in the least with the balance of the rig and machinery. It also enables the driller to pump cement in between any two strings of pipe instead of pumping the same down the inside casing and around the bottom. The concrete foundation and the heavy metallic base member 1 insures the proper arrangement of the couplings and the pipes carried thereby in true vertical positions.

In the drawings I have shown a number of bushings which may be successfully employed in connection with my improvement, but I do not wish to be restricted to the construction illustrated, as I may, at a later date, find it convenient to employ other means. Therefore, my invention is to be restricted only by the scope of what I claim.

Having described the invention, I claim:

1. In a device for the purpose set forth, a pipe let in an oil well and having its outer end projecting beyond the ground surface, a concrete foundation body arranged around the said end of the pipe, a metal base resting on the foundation having a central opening of an area approximately equalling that of the pipe, other pipes of different diameters to be received one in the other and in the first mentioned pipe, bushings on the outer end of each of the last mentioned pipes resting upon each other and the lowermost bushing resting on the metal base, a packing between the bushings and base, each of said bushings having spaced longitudinal passages in the outer periphery thereof, each of said bushings having a circumferential depression with which the passages of the adjacent bushings communicate, each bushing having a threaded port communicating with the depression therein, and each of said ports being valve controlled.

spaced longitudinal passages in the outer periphery thereof, each of said bushings having a circumferential depression with which the passages of the adjacent bushings communicate, and each bushing having a threaded port communicating with the depression therein.

2. In a device for the purpose set forth, a pipe let in an oil well having its outer end projecting above the ground surface and a coupling screwed thereon, a concrete foundation body arranged around said end and said coupling, a metal base resting on the foundation having a central opening approximately equalling the area of the coupling, said base having its upper face formed with ribs which are apertured, a headed bushing received through the opening in the base and having its head resting on the base, a pipe secured thereon entering the first mentioned pipe, the head of said bushing having a circumferential depression and threaded ports communicating therewith, a hydraulic packing between the head of the bushing and the base, other headed bushings each carrying a pipe received one within the other and having their stem portions snugly engaging the bore of the adjacent bushing, the heads of each of the last mentioned bushings having an annular depression and having threaded ports communicating therewith, the stems of each of the last mentioned bushings having longitudinal passages communicating with the depressions, and the heads of all of the bushings having outstanding oppositely opposed downwardly rounded ears, for the purpose set forth.

3. In a device for the purpose set forth, a pipe let in an oil well and having its outer end projecting beyond the ground surface, a concrete foundation body arranged around the said end of the pipe, a metal base resting on the foundation having a central opening of an area approximately equalling that of the pipe, other pipes of different diameters to be received one in the other and in the first mentioned pipe, bushings on the outer end of each of the last mentioned pipes resting upon each other and the lowermost bushing resting on the metal base, a packing between the bushings and base, each of said bushings having spaced longitudinal passages in the outer periphery thereof, each of said bushings having a circumferential depression with which the passages of the adjacent bushings communicate, each bushing having a threaded port communicating with the depression therein, and each of said ports being valve controlled.

In testimony whereof I affix my signature.

FRANK REDICK.
